UNITED STATES PATENT OFFICE

ERWIN HUGH HAMILTON, OF HASTINGS, NEW YORK

THROTTLING STEAM-CALORIMETER CONSTRUCTION

Application filed April 15, 1925. Serial No. 23,436.

My invention relates to improvements in throttling steam calorimeter construction.

It is one object of my invention to make easier the use of such a calorimeter whereby the quality of steam or the amount of moisture carried in suspension in the current of steam is determined.

Heretofore, serious difficulty has been experienced in determining the temperature corresponding to the boiling point for the particular pressure existing inside the calorimeter. In some types of calorimeters this temperature is assumed, in others the pressure is determined by means of a manometer and then, with the aid of steam tables, the boiling point is determined.

It is further the object of my invention to, first, simplify the construction of the calorimeter itself; second, to simplify the operation of such an instrument; third, to provide a calorimeter in which all readings are made on the same thermometer; fourth, to provide a calorimeter in which it is not necessary to measure the pressure inside of the calorimeter, nor is it necessary to assume this pressure; and fifth, to provide a calorimeter in which the steam entering the calorimeter is expanded adiabatically from the steam line pressure down to the calorimeter pressure by means of a nozzle having both a convergent and also a divergent section.

I attain these objects by the mechanism illustrated in the accompanying drawing, in which—

Figure 1 is a vertical section of the entire apparatus. Figure 2 is a section taken along the line AA thru the water jacketed inlet pipe of the calorimeter.

Similar numerals refer to similar parts throughout the drawing.

The steam main or line 12 is shown as having a sampling tube 10 projecting into it. A valve 1 is placed in the line joining the sampling tube with the calorimeter. Part of the line 16 joining the sampling tube with the calorimeter is surrounded by, or in contact with, a waterjacket 6. The water inlet to this water jacket is marked 17 and is equipit with a valve 3. The outlet from the jacket is marked 5. This outlet is equipit

with a valve marked 4. Between the line 16 and the calorimeter is located a heat insulating disk 14. This insulating disk is used to prevent a flow of heat from the calorimeter back to the water jacket. The calorimeter inlet 15 is made in the form of a Venturi tube, that is a tube having a convergent section and also a divergent section. The purpose of this Venturi tube or nozzle is to expand the steam adiabatically from the high pressure of the steam line down to the calorimeter pressure. The ratio of throat area to end area in this Venturi tube, and the length of the convergent and divergent sections may be varied and will depend somewhat on the steam pressure for which the calorimeter is designed.

The calorimeter 11 may be of any shape whatever. It may be uncovered as shown, or it may, and preferably should be covered with heat insulating material. It may have a thermometer-well as shown, or the thermometer may be connected to the steam space in any other manner desired.

The steam outlet from the calorimeter is marked 9 and is equipit with a valve 2.

The method of operating this calorimeter is as follows:—

Valves 2 and 3 are closed. Valves 1 and 4 are opened. At this time the steam from the steam main fills the calorimeter up to the pressure in the main. The temperature read on the thermometer at this time is therefore the temperature of the steam in the steam line. Next valves 2 and 3 are opened and valve 4 is closed. The temperature read on the thermometer with this setting of the valves is the temperature of the boiling point of steam at the pressure existing inside of the calorimeter. Next valve 3 is closed and valve 4 is opened to remove the water from the water jacket. The steam then flowing through the calorimeter becomes superheated and the temperature read on the thermometer at this time is the temperature of the superheated steam existing in the calorimeter.

From these three temperatures the quality of the steam in the steam main can be obtained by means of steam tables and a simple calculation in well known manner.

I am aware that prior to my invention,

throttling steam calorimeters have been used. I therefore do not claim such a construction broadly.

I claim:

- 5 1. A device for determining the quality of steam in a steam main comprising a chamber, a connection between a steam main and said chamber, a water jacket for said connection, and means controlling the admission of steam to said chamber and the flow of water in said water jacket whereby both saturated and superheated steam may be produced at will in said chamber at the same pressure.
- 10 2. A device for determining the quality of steam in a steam main comprising a chamber, a thermometer in said chamber, a connection between a steam main and said chamber, means controlling the admission of steam to said chamber, means for cooling said connection and means for controlling the cooling means whereby saturated or superheated steam may be produced in said chamber at the same pressure, and the temperature of both the saturated and superheated steam 25 may be read on said thermometer.
- 15 3. A device for determining the quality of steam in a steam main comprising a chamber, a thermometer in said chamber, a connection between a steam main and said chamber, a valve for said connection, a water jacket for said connection, inlet and outlet connections to said water jacket, a heat insulating disk in said connection, an outlet for said chamber, and a valve for said outlet.
- 20 4. A throttling calorimeter comprising a thermometer, a chamber therefor, a connection therefrom to a steam main, a plurality of connections in communication with said chamber and controllable so that the temperature of the steam in the steam main, the temperature of the boiling point of the steam corresponding to the pressure existing in the calorimeter and the temperature of superheated steam in said calorimeter may each be 25 read at will on said thermometer, the latter two temperatures being taken at a pressure below steam main pressure.
- 25 5. A throttling calorimeter comprising a thermometer, a chamber therefor, a connection therefrom to a steam main, and controllable means for varying the conditions in said calorimeter whereby the temperature of the steam in the steam main, the temperature of the boiling point of the steam corresponding to the pressure existing in the calorimeter and the temperature of superheated steam existing in the calorimeter may each be at will 30 read on said thermometer.
- 35 6. The method of determining the quality of steam in a steam main which comprises obtaining the readings for the temperature of the steam in the steam main, for the temperature of the boiling point of the steam corresponding to the pressure existing in the calorimeter and for the temperature of the 35

steam superheated existing in the calorimeter upon a single thermometer, which consists in connecting a chamber to a steam main, the chamber having a thermometer connected thereto, and creating the varying conditions in said chamber.

- 70 7. A device for determining the quality of steam in a steam main comprising a chamber, a thermometer in said chamber, a connection between a steam main and said chamber, the connection having a convergent portion terminating in a constriction and a divergent portion therefrom terminating in said chamber, means controlling the admission of steam to said chamber, means for cooling said connection, and means of controlling the cooling means whereby saturated or superheated steam may be produced in said chamber at the same pressure and the temperature of both the saturated and superheated steam may be read on said thermometer.
